(57) **CLAIM**

The ornamental design for an image for a portion of a display screen, as shown and described.

DESCRIPTION

FIG. 1 is a front view of a image for an portion of a display screen showing our new design; and,

FIG. 2 is an enlarged view of the claimed region.

The broken line showing of various regions in the figures and the unshaded areas there within form no part of the claimed design. The broken line showing of the display screen is for illustrative purposes only and forms no part of the claimed design.

1 Claim, 2 Drawing Sheets

FIG. 2
